(74) *Attorney, Agent, or Firm* — Christopher C. Dremann, P.C.; Christopher C. Dremann(57) **CLAIM**

The ornamental design for a hydraulic grease coupler, as shown and described.

DESCRIPTION

1.-2. Hydraulic grease couplers

1.1 : Perspective

1.2 : Left

1.3 : Top

1.4 : Bottom

1.5 : Front

1.6 : Back

2.1 : Perspective

2.2 : Left

2.3 : Top

2.4 : Bottom

2.5 : Front

2.6 : Back

Design 1 shows a hydraulic grease coupler (with a rotary connection) to couple an outlet of a grease gun and a grease

(Continued)

nipple; design 2 shows a hydraulic grease coupler (with a rotary connection) to couple an outlet of a grease gun and a grease nipple.

The portions of the hydraulic grease couplers shown in broken lines form no part of the claimed design.

1 Claim, 12 Drawing Sheets
